United States Patent Office

Des. 227,143
Patented June 5, 1973

227,143

COFFEEMAKER

Julian R. Haynes, Hinsdale, Ill., assignor to Sunbeam
Corporation, Chicago, Ill.

Filed Dec. 16, 1971, Ser. No. 208,516

Term of patent 14 years

Int. Cl. D7—04

U.S. Cl. D44—26 A

Fig. 1.

Fig. 2.

Fig. 3.

FIG. 1 is a perspective view of a coffeemaker showing my new design;

FIG. 2 is an enlarged side elevational view showing the side opposite that shown in FIG. 1;

FIG. 3 is an enlarged top view thereof;

FIG. 4 is an enlarged front elevational view thereof; and

FIG. 5 is an enlarged rear elevational view thereof.

I claim:

The ornamental design for a coffeemaker, as shown.
